UNITED STATES PATENT OFFICE.

HENRY FREDERICK FARRAR SEDGWICK, OF MILLWALL, LONDON, ENGLAND.

BENDING-MACHINE.

1,306,126.

Specification of Letters Patent. Patented June 10, 1919.

Application filed March 6, 1918. Serial No. 220,840.

To all whom it may concern:

Be it known that I, HENRY FREDERICK FARRAR SEDGWICK, a subject of the King of Great Britain, residing at 36 West Ferry road, Millwall, E., in the county of London, England, have invented certain new and useful Improvements in or Relating to Bending-Machines, of which the following is a specification.

10 This invention has reference to machines for bending metal sheets and for like purposes, and relates more particularly to an improved construction of machine having a table comprising one or more movable or 15 hinged flaps on which the sheet or piece of work is laid and by which it is bent up around the edge of a clamping rail.

One object of the invention is to enable sheets or plates to be bent up to practically 20 any desired angle, on one or both sides.

To this end the parts may be so arranged that when the movable flap, or each flap, is raised there is always a sufficient space between it and the clamping rail or presser 25 bar, to accommodate the thickness of the metal sheet or plate. In this way strains and damage to the machine, such as are liable to occur where such space or clearance is not provided for, are entirely obviated. That is to say the metal at the angle, 30 although it may be say a quarter or half an inch or more in thickness, is not nipped or compressed between the edge of the flap and the clamping rail, but is simply bent around 35 the latter.

A feature of the invention consists in an improved hinging arrangement for the movable flap or flaps, capable of holding the same securely even when considerably raised 40 and standing more or less on edge.

A further feature of the invention consists in so arranging the hinges or pivots that the flaps turn on axial or center lines which are slightly separated, the distance of the 45 said axial lines being a little more than double the thickness of the thickest sheet or heaviest work which the machine is intended to deal with.

In order that the invention may be clearly 50 understood and readily carried into effect, reference will now be had by way of example, to the accompanying diagrammatic drawings in which:

Figure 1 is a transverse section of one

construction of the improved machine having the improved hinging arrangements. 55

Fig. 2 is a part plan view of the hinging arrangements.

Fig. 3 is a side view of a stationary and a 60 movable member of the hinge.

Fig. 4 is a transverse section on the line 4-4 of Fig. 3 showing three adjacent hinge blocks slightly separated for the sake of clearness.

In the example illustrated, *a* and *a'* are 65 the movable portions or table flaps which are supported by end frames or pedestals *b*. They are arranged so that their adjacent edges lie under or parallel with an adjustable presser bar *b*.

The said movable flaps *a* *a'* are worked by segmental gearing or toothed quadrants *c* connected to their undersides and projecting downward and inward as shown. They are operated by pinions *e* driven from a 70 gear-train such as *f* *f'* *f''* at one or both ends of the machine, these gears being actuated by a motor *g* or otherwise.

The hinging of the movable portions or flaps *a* *a'* is effected by annular or semi-circular projections *h* at each side of blocks *i* which form the inner ends of arms or stiffening brackets *i'* extending across the undersides of the flaps and arranged side by side (see Fig. 2) at intervals along them. 80 Carried by the center frame or bed *j* of the machine, under the middle or hinge part of the table, are a series of supporting blocks *j'* alternating with the blocks *i*. They have corresponding annular grooves 85 *h'* in their side faces to receive the annular tongues or part-hoops *h*. These grooved blocks *j'* act as guides for the curved tongues *h* on the blocks *i*, and the two sets of blocks constitute the hinges for the 90 table.

The arrangement may conveniently be 95 such that a projection or tongue *h* of one flap fits laterally into the groove *h'* at one side of a block, while that of the other flap fits into the other side. This construction 100 gives a distributed support all along the underside of the hinge, and the lateral engagement of the partly hoop-like projections *h* in the grooves insures the firmness 105 of the hinge at all angles. This is the case not only when the strain is downward or vertical, that is to say toward the hinge

blocks as when the flaps are nearly horizontal, but also when the strain comes laterally and outward, as it does when the flaps are considerably raised, and the resulting pressure on the work between them tends to force their adjacent edges apart.

Without the positive engagement of the hoop-like or U-shaped pieces in the grooves of the supporting blocks j^1 there would be considerable risk of the middle edges of the table springing or being forced apart in the manner referred to, when in or near its extreme position, and the machine might be damaged.

15. In order to allow the spacing apart of the axes of the two flaps, the guide or hinge groove h^1 in one side of each block may be set a little out of alignment with that in the other side. In other words the centers of 20 the two grooves lie alternately on opposite sides of the true center line of the machine, which is practically just below the bottom edge line of the presser or clamping bar. Thus as the flaps rise they allow a 25 corresponding clearance at each side of the lower part of the said bar, between the bottom tip of the bar and the adjacent edge of the flap. The hinge block seen in Fig. 1 is a section on the line 1—1 of Fig. 2.

30. In some machines only one flap may be movable, the other being stationary.

Moreover the projecting tongues may be arranged on the blocks j^1 and the grooves be in the blocks i or partly in one and 35 partly in the other.

By varying the height of the presser bar b the nature of the bend can be altered. Thus if the presser is in its lowest position a sharp angle or corner is formed in the 40 bent plate, whereas if it is raised, the bend acquires an easy curvature.

It will be seen that a gap or space is left between the inner edges of the flaps, and as these edges ought to coincide with the 45 centers of the hinges, the said gap therefore equals the amount by which the two sets of hinge blocks are out of line.

The gap serves to give the necessary space around the bottom edge of the presser rail 50 when the flaps are raised, thus avoiding jamming or strain. The width of said gap is slightly more than double the thickness of the stoutest work the machine is intended to deal with. It also serves to receive any 55 scale or pieces that may drop from the plates, which otherwise might damage the machine if the edges met closely.

To further prevent strains on the machine, means may be provided for automatically cutting off the driving power either 60 when the table flaps are raised or when they

are returned to their exact horizontal position again, or at both of these times.

This may be done for example by spring-actuated belt shifters, or if the drive is an 65 electric one, by interlocked cut-out switches, one of which acts when at the end of the rising movement and the other at the end of the descending or return movement.

Although intended for sheets or plates of 70 appreciable thickness, the machine may also be used for light, thin sheets if desired.

Obviously the invention may be modified in various ways in carrying the same into effect without departing from the general nature thereof. 75

I claim:—

1. In a machine for bending metal sheets or for like purposes, the combination of a frame, a stationary V-shaped presser-bar 80 having its ends supported in said frame, two flaps adapted to fold down into line with each other, stationary hinge blocks distributed at intervals along the bed of the machine and arranged alternately with movable blocks distributed along the flaps, a rigid supporting bar carrying said stationary hinge blocks, projecting annular tongues on certain of said blocks engaging in annular grooves in the other blocks, toothed 85 quadrants of equal diameter secured below the flaps and toothed gearing for raising and lowering said flaps, substantially as described.

2. In a machine for bending metal sheets, 90 the combination of a frame, a stationary adjustable presser bar, hinged flaps mounted in said frame but with a gap between their adjacent edges, the alternate hinges being centered slightly toward opposite 100 sides of the axis of the machine, toothed quadrants of equal diameter secured beneath the flaps for raising and lowering the flaps, and gearing for operating said quadrants, substantially as described. 105

3. In a machine for bending metal sheets, the combination of a frame, hinged flaps, a stationary bar arranged on edge midway above the gap between the adjacent edges of said flaps, hinges distributed along said 110 flaps with their centers toward opposite sides of said bar, a rigid central bar arranged lengthwise below the flaps to carry the fixed parts of said hinges, toothed quadrants of equal diameter secured below the 115 flaps, and pinions for operating said quadrants, such pinions being driven at equal speeds from one and the same train of wheels, substantially as described.

In testimony whereof I affix my signature. 120

HENRY FREDERICK FARRAR SEDGWICK.
